Application October 8, 1938, Serial No. 80,334

Term of patent 7 years

To all whom it may concern:

Be it known that we, Melvin Nelson, Walter R. Hultberg and Herbert Dahl, citizens of the United States, residing at Corry, in the county of Erie and State of Pennsylvania, have invented a new, original, and ornamental Design for a Desk, of which the following is a specification, reference being had to the accompanying drawings, forming part thereof; and in which—

Figure 1 is a front perspective view of a desk showing our new design;

The characteristic features of our design reside in a desk having smooth, plane surfaced end panels terminating in rolled edges, the upper edges of which form end margins for a top panel and the front and rear edges forming margins for pedestal drawers and rear panels respectively, substantially as shown in the drawings.
